UNITED STATES PATENT OFFICE.

SAMUEL S. YARRINGTON, OF WILMINGTON, DELAWARE.

FLYING-MACHINE.

1,006,335.

Specification of Letters Patent. Patented Oct. 17, 1911.

Application filed December 3, 1910. Serial No. 595,403.

To all whom it may concern:

Be it known that I, SAMUEL S. YARRINGTON, a citizen of the United States, residing at Wilmington, in the county of Newcastle and State of Delaware, have invented new and useful Improvements in Flying-Machines, of which the following is a specification.

This invention relates to flying machines 10 of the heavier-than-air type, the object of the invention being to provide means for securing automatic lateral and longitudinal stability and for affording complete manual control, as well as to provide means for 15 preventing lateral deflection of the machine from its course of travel and facilitating and rendering safer the operations of launching and landing.

The invention consists of the features of 20 construction, combination and arrangement of parts, hereinafter fully described and claimed, reference being had to the accompanying drawings, in which:—

Figure 1 is a top plan view of a flying 25 machine embodying my invention. Fig. 2 is a front elevation of the machine. Fig. 3 is a rear elevation of the same. Fig. 4 is a side elevation of the machine. Fig. 5 is a detail section, showing the clutch connection 30 between the gyroscope and its drive shaft. Fig. 6 is a diagrammatic view of the manually controlled stabilizers and means for 35 operating the same. Fig. 7 is a similar view of the vertical rudders and means for operating the same. Fig. 8 is a view of the operating mechanism for controlling the auxiliary planes.

Referring to the drawings, 1 designates the main frame of the machine, which may 40 be provided with any suitable type of launching and landing gear, that shown in the present instance consisting of supporting wheels 2 yieldingly mounted in any preferred manner for a cushioning action in the 45 launching and landing operations.

Rising from the front and rear portions of the main frame are standards or uprights 3, which carry front and rear supporting planes or surfaces 4, extending 50 transversely of the frame or at right angles to the line of flight and suitably curved between their front and rear edges for the supporting action of the air thereon. These supporting surfaces 4 are separated by an 55 intervening transverse space or gap 5 of

sufficient width to allow the air acting upon the surface of the front supporting surface 4 to freely escape at the rear edge of said surface and assume its normal density before acting upon the surface of the rear supporting surface 4, whereby a substantially equal supporting effect upon both the said surfaces will be secured.

The operator's seat 6 is arranged upon the main frame at a suitable point between the front and rear extremities thereof, and disposed upon said frame in advance thereof is a horizontal rudder 7 for vertical steering, said rudder preferably consisting of a pair of superposed, curved planes or surfaces 7' pivotally mounted upon the proper supports to tilt in unison. This rudder is connected by a link rod 8 with a standard 9 disposed in front of and adjacent to the seat 6 and connected with the main frame by a universal joint 10, by which it is adapted to swing longitudinally and laterally. A hand wheel 11 is suitably journaled upon the upper end of this standard, whereby the latter may be conveniently operated.

Disposed upon the rear portion of the main frame is a fixed balancing or stabilizing device 12, preferably consisting of a pair of superposed, rigidly mounted curved planes or supporting surfaces 12', coextensive in size or substantially so with the surfaces 7' of the front horizontal rudder 7, said fixed balancing device having a supporting action substantially equal to that of the front horizontal rudder when the latter is in normal or neutral position, whereby the tendency of the machine to tilt in a fore and aft direction under the pressure of the surfaces of the horizontal rudder when the latter is in normal position is neutralized, giving greater fore and aft stability to the machine.

A vertical rudder 13 is pivotally mounted to swing laterally upon the main frame below the balancing device 12 and is subjected to the pressure of the condensed air displaced downwardly therefrom, whereby said rudder is adapted to move against a bank of air in either direction so that the resistance of the air thereon will be increased and the sensitiveness of steering action of the rudder enhanced. As shown, the rudder 13 preferably consists of a pair of vertical surfaces connected to move in unison by a transverse link 14, to which are connected the crossed

rear ends of wires or cables 15 passing forwardly over suitable direction pulleys 16 and connected at their forward ends to opposite sides of the standards 9, whereby through reverse lateral movements of said standards the rudder planes may be simultaneously adjusted in one direction or the other to steer the machine in a horizontal plane. Driving propellers (one or more) 17 are journaled upon the frame at a point in advance of and adjacent to the balancing device and vertical rudder, and may be operated by any suitable type of motor and drive gearing, not shown. The air displaced by the blades of these propellers is thrown rearwardly in the path of the balancing device and vertical rudder, thus increasing their stabilizing and steering effect.

Suitably journaled upon the main frame and extending upwardly at the center of the same into and above the cap or space 5 is a vertical shaft 18, which may be driven in practice from the propeller driving motor or frame and auxiliary motor, as desired. The upper end of this shaft is stayed from the frame portions of the supporting surfaces 4 by suitable guys or braces 19, and mounted upon said shaft to rotate horizontally in the space 5 between the supporting surfaces is a lifting wheel 20. This wheel is fixed upon the shaft and its blades are properly pitched for an efficient lifting action when the wheel is rotated in one direction, whereby the machine may be elevated to any desired height and its descent controlled in making a landing. When the machine is in flight the wheel may be revolved at just sufficient speed to adapt it to cooperate with the supporting surfaces to sustain the machine, as will be readily understood. Also mounted on the shaft 18, preferably below the lifting wheel 20 is a horizontally revoluble gyroscopic wheel 21, which normally rotates with the shaft and lifting wheel, at all times when the same are in action. The hub 22 in this gyroscope wheel is loosely mounted on the shaft 18 and a clutch device is provided for locking it to said shaft when the latter is in motion to free it for independent revoluble movement on the shaft when the motion of the latter is arrested or reduced below a prescribed speed. This clutch device comprises a pivoted dog 23 carried by the hub 22 and working in a slot 24 therein, which dog is adapted to engage a ratchet recess 25 formed in the shaft, said recess having the usual beveled face and abrupt end shoulder. The dog is normally held yieldingly in engaging position by a spring 26, the construction being such that when the shaft 18 is in motion the shoulder of the recess 25 will engage the dog and thus lock the gyroscope wheel to the shaft for rotation at the same rate of speed therewith. When the motion

of the shaft 18 is suddenly arrested, or the speed thereof reduced below the speed of revolution of the gyroscope wheel under attained momentum of the latter, the dog 23 will ride out of the recess over the beveled face thereof and the wheel will continue to revolve until the force of its momentum is spent. Hence, it will be apparent that if the motion of the shaft 18 is arrested or its speed materially reduced at any time in the operation of landing or when the machine is coasting or descending from a higher to a lower level, the gyroscope will still maintain a velocity sufficient to maintain the balance of the machine, giving more thorough and effective control thereof.

Frame structures 27 extend laterally at the opposite sides of the machine from the frame portions of the surfaces 4 and carry auxiliary longitudinally extending supporting surfaces or wings 28, which are concavo-convexly curved in a transverse direction and preferably extend the full distance of the machine from front to rear. The said wings are pivotally connected at their rear ends, as at 29, to the frame portions of the rear supporting surface 4 and extend upwardly and forwardly at a more or less negative angle of inclination, so that the supporting action of the air thereon when the machine is in flight will be sufficient to promote sustentation but not sufficient to cause any rearward tilting or tendency to loss of any of the fore and aft balance. The forward ends of the wings 28 slidably engage guide rods 30 which are pivotally connected at their lower ends to the front frame portions of the front supporting surface 4, said wings thus being adapted to slide vertically on the rods for a warping or flexing action, whereby their angle of incidence may be varied as desired. Springs 31 encircle the rods and normally operate to hold the front ends of the wings 28 elevated, such springs being compressed upon the downward movement of the wings and the rods allowed by their pivotal mounting to swing to accommodate themselves to varying angles of inclination of the wings.

The wings 28 are adapted to be drawn downwardly, warped or tilted by controlling connections consisting of a cord or cable 32 having a looped portion 33 passing around suitable direction pulleys 34 and 35 on the wings are pivotally connected at their rear 33 thence extending over suitable pulleys 36 and 37 to a point adjacent the operator's seat where they are connected with the grooved periphery of a controlling wheel 38 journaled upon a suitable supporting bracket 39. By turning this wheel in one direction the cables may be simultaneously drawn upon and the wings depressed, thus varying their angle of inclination so that they will operate as supporting surfaces for

utilization in launching the machine or acting as a wind brake to check the rate of speed of descent of the machine, thus enabling the operator to avert possible disaster when the machine is coasting or landing at an excess speed. Upon turning the wheel in the reverse direction the springs will restore the wings to normal position. In order that the wings may be adjusted 10 and held at any desired angle, the shaft of the wheel 38 is provided with a ratchet disk 40 engaged by a spring actuated locking pawl 41 connected by a link 42 with a pedal or foot lever 43, the spring normally holding the pawl in locking position, while through a movement of the lever 43 the operator may retract it against the resistance of the spring to enable the wheel 38 to be turned to adjust the wings.

20 Arranged at the rear of the machine below the rear supporting surface 4 and adjacent the lateral margins thereof are vertically movable ailerons or balancing planes 44 pivoted at their forward ends to the frame, as at 45. To the rear or free ends of these ailerons are respectively connected forwardly and downwardly extending wires or cables 46 and 47 leading over suitable direction pulleys to the grooved periphery of 30 the controlling wheel 11, about which the connected or looped forward ends of the respective sets of cables are wound in reverse directions, so that upon turning the wheel in one direction one of the ailerons will be depressed and the other elevated, while upon turning the wheel in the reverse direction a reverse adjustment of the ailerons will be effected. These ailerons are employed for controlling the lateral balance of the machine under divers conditions and banking 40 the machine in making a turn, as will be readily understood.

Owing to the fact that the lifting wheel 20 in action has a side thrust of air tending 45 to deflect the machine laterally from its curve in the direction opposite to the direction of rotation of the wheel, it is desirable to provide some means for opposing and neutralizing its lateral thrust to maintain the machine in flight on a straight course. To this end I employ a counteracting agent preferably in the form of a propeller 49 mounted to rotate vertically in a fore and aft direction on a horizontal axis arranged 50 at the front of the machine, the blades of which propeller are pitched to set up a side thrust tending to laterally deflect the machine in the opposite direction to the thrust tendency of the lifting wheel, the thrust 55 pressures being as far as possible for the same so that they will neutralize each other, by which the tendency of the lifting wheel to deflect the machine laterally will be opposed and counteracted. The propeller 49 60 may be driven by a belt 50 from the motor

which operates the driving propeller or motor which operates the lifting wheel shafts, as may be found most serviceable in practice.

Having thus described the invention, I claim:—

1. A flying machine including a main frame, upright frames rising from the front and rear of the main frame, transversely extending supporting surfaces carried by said upright frames, a vertical shaft journaled 70 at its lower end upon the center of the main frame and projecting upwardly between said upright frames, drive mechanism on the main frame for operating said shaft, a lifting propeller mounted on said shaft above 75 the main frame and between said upright frames, and a gyroscope wheel mounted in said shaft between the lifting wheel and the main frame, said gyroscope wheel having a clutch connection with the shaft operative 80 to permit independent motion of said wheel under its momentum upon the cessation of motion of said shaft.

2. A flying machine including a main frame, upright frames at the front and rear 90 of the main frame, transversely extending supporting surfaces carried by said upright frames, longitudinally extending supporting surfaces hinged at their rear ends to the extremities of the rear upright frame and arranged at right angles to said transverse supporting surfaces, said longitudinally extending supporting surfaces projecting forwardly at an upward angle, means yieldingly supporting and connecting the forward end of the longitudinally extending supporting surfaces with the front upright frame, and means connected with the front ends of said longitudinally extending supporting surfaces for depressing the same. 100

3. A flying machine including a main frame, upright frames at the front and rear 110 of the main frame, transversely extending supporting surfaces carried by the upright frames, longitudinally extending supporting surfaces arranged at right angles to the transversely extending surfaces, hinged at their rear ends to the rear upright frame and inclining upwardly and forwardly therefrom, means yieldingly connecting the forward ends of the longitudinally extending supporting surfaces with the front upright frame, and means for drawing the front ends of the longitudinally extending supporting surfaces downward against the resistance of said supporting means. 115

4. In a flying machine, a gyroscope wheel, a drive shaft therefor, driving mechanism coupled to said shaft and a clutch connection between said wheel and shaft operative 125 to permit independent motion of said wheel under its momentum upon the cessation of motion of said shaft.

5. In a flying machine, a horizontally disposed gyroscope wheel, a vertical drive 130

shaft therefor, driving mechanism coupled to said shaft and a clutch connection between said wheel and shaft operative to permit independent motion of said wheel under 5 its momentum upon the cessation of motion of said shaft.

6. In a flying machine, a vertical driving shaft, a horizontally arranged lifting wheel mounted on said shaft, driving mechanism 10 coupled to the shaft, a horizontally revoluble gyroscope wheel mounted on the shaft, and a clutch connection between said wheel and shaft operative to permit independent motion of said wheel under its momentum upon 15 the cessation of motion of said shaft.

7. In a flying machine, a vertical drive shaft having a clutch recess provided with an inclined wall and a shoulder, a lifting wheel carried by said shaft, a motor for 20 driving said shaft, a gyroscope wheel loosely mounted on the shaft, and a spring actuated clutch carried by the wheel and coöperating with the recess to connect said gyroscope wheel with the shaft and to permit 25 independent revolution of said wheel upon the cessation of motion of said shaft.

8. A flying machine, the combination of a main frame, front and rear pairs of superposed supporting surfaces carried thereby, 30 said surfaces being arranged at an elevation above the main frame, a vertical shaft extending upwardly between said supporting surfaces, a lifting propeller carried by said shaft, a gyroscope wheel mounted on the 35 shaft between the main frame and lifting propeller, a motor on the main frame for driving said shaft, a horizontal transversely disposed shaft at the front of the main frame, and a non-lifting propeller mounted 40 on said shaft and rotatable in a fore and aft direction for counteracting the deflecting action of said lifting propeller.

9. In a flying machine, the combination of a frame, transversely extending supporting surfaces at the front and rear of the 45

frame, longitudinally extending wings at the sides of the frame pivotally mounted at their rear ends and inclining upwardly and forwardly at an angle therefrom, pivotally mounted guide rods slidably engaged by the 50 front ends of the wings, coiled springs surrounding the rods and yieldingly supporting the front ends of the wings, and means for simultaneously adjusting said wings bodily in the same direction to change their 55 angle of incidence.

10. In a flying machine, the combination of a frame, transversely extending supporting surfaces at the front and rear of the frame, longitudinally extending wings at 60 the sides of the frame pivotally mounted for vertical movement at their rear ends and inclining upwardly and forwardly at an angle therefrom, supports slidably engaged by the 65 front ends of the wings, means associated therewith for holding the wings elevated, and means for simultaneously adjusting said wings bodily in the same direction to change their angle of incidence.

11. In a flying machine, the combination of a frame, transversely extending supporting surfaces at the front and rear of the frame, longitudinally extending wings at 70 the sides of the frame pivotally mounted at their rear ends for vertical movement and 75 inclining upwardly and forwardly at an angle therefrom, pivoted supports slidably engaged by the front ends of the wings, springs carried by said supports and acting upon the wings to normally hold the same 80 elevated, and means for simultaneously adjusting said wings bodily in the same direction to change their angle of incidence.

In testimony whereof I affix my signature in presence of two witnesses.

SAMUEL S. YARRINGTON.
